[57] CLAIM

The ornamental design for a sprayer head, as shown and described.

DESCRIPTION

FIG. 1 is a front elevational view of a sprayer head showing our new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof.

The broken line drawing of a container is for illustrative purposes only and forms no part of the claimed design.

FIG. 1

FIG. 2

FIG. 3

FIG. 4
